CLAIM

The ornamental design for a seat, as shown and described.

DESCRIPTION

FIG. 1 is a front perspective view of a seat showing my design in the form of a settee;

FIG. 2 is a top plan view;

FIG. 3 is a rear elevational view;

FIG. 4 is an end perspective view;

FIG. 5 is a rear perspective view thereof;

FIG. 6 is a front perspective view of a seat showing my design in the form of a sofa;

FIG. 7 is a top plan view; and

FIG. 8 is a rear elevational view thereof.

The end of the settee not shown is a mirror image of the end shown in FIG. 4 while the undisclosed ends of the sofa form are the same in appearance as the respective ends of the settee.
